UNITED STATES PATENT OFFICE

PEARL JOSEPH WENTWORTH, OF FORT THOMAS, KENTUCKY

MACHINE FOR TRIMMING SOLE MARGINS

Application filed August 9, 1926. Serial No. 128,067.

This invention relates to improvements in shoe machinery and more particularly to a machine for marginally trimming or scarfing a shoe sole before securing the sole to the upper to produce a uniform surface finish marginally on one side of the sole.

The machine provides a pair of driven feed rolls between which the material or shoe sole is inserted and a stationary knife definitely set in relation to one of the rolls and movable as a unit with said roll transversely to the direction of feed of the work to automatically position the cutter with respect to the surface of the work so that no change in setting of the cutter need be made for operating upon different pieces of work of varying thickness. The roll and blade as a unit are pressed upon the work and against the periphery of the second roll which prevents the cutter from digging into the work beyond a determined depth cut.

Therefore, an object of the invention is to provide a trimming or scarfing machine for trimming the margin of one side of a shoe sole to produce a finished face surface, the machine operating upon sole blanks of varying thickness without requiring a change in the cutter setting.

Another object of the invention is to provide an edge trimming or scarfing machine with a pair of feed rolls one of which is mounted for compressingly engaging the work inserted between the rolls to feed the same with the rotation of the rolls, and a stationary cutter mounted for movement as a unit with said movable roll toward and from the second roll, adapting the cutter to be automatically adjusted for operating upon pieces of work of relatively different degrees of thickness through the introduction of the work between the rolls.

Other objects and certain advantages will be more fully set forth in the description of the accompanying drawings forming a part 45 of this specification in which:

Figure 1 is a front view of the cutting machine, certain portions thereof being shown in section to illustrate the mounting of the various parts.

Figure 2 is a sectional view taken on line 2—2 of Fig. 1, showing the gearing connections between the feeding shafts and the manually operated shaft.

Figure 3 is a sectional view on line 3—3 of Fig. 1, showing the means for raising the blade and the upper feeding member away from the lower support and feeding member when a shoe sole is to be inserted.

Figure 4 is a sectional view taken on line 4—4 of Fig. 3 showing the relation of feeding members and cutting element, and showing a shoe sole inserted in the mechanism with the desired cut being made on the margin thereof.

Figure 5 is a sectional view taken on line 5—5 of Fig. 4 detailing the cutter element structure and showing the relation of the shoe sole to the blade during the scarfing operation.

Figure 6 is a view of the blade removed from the cutter element.

Figure 7 is a view showing a form of support and feeding member for disposing the shoe sole edge at a proper angle to the cutter blade for the removal of a greater amount of material therefrom.

Figure 8 is a front view of the cutter element showing the relation of the guide member to the base cutter blade.

The invention herein is primarily directed to feeding and cutting instrumentalities for chamfering or trimming the edge of a leather shoe sole in which a stationary cutter is disposed relatively to a pair of feed rolls for trimming the marginal surface or edge of the material, fed by and engaged between the rolls with the cutter mounted for unit movement with one of the rolls toward and from the second roll. The frame structure for supporting the rolls and cutter and the trans-

mission for rotating the rolls may be of any conventional form, the type herein illustrated being adapted to be mounted upon a bench and comprising a U-shaped frame formed of a base 1 and spaced uprights 2, 2^a, for supporting and journaling the several shafts providing the transmission for the feed rolls. The transmission is shown as hand-crank operated and comprises a driving shaft 3 having a hand crank 4 fixed thereon at one end. The shaft 3 also carries a gear 5 fixed thereon preferably adjacent the inner side of the upright 2, the gear 5 and crank handle 4 being relatively mounted on opposite sides of the upright serving to secure the shaft within its bearing against longitudinal displacement. The gear 5 is in mesh with the gear 8 on an intermediate shaft 6, the shaft 6 at its outer end carrying one of the feed rolls, in this instance the lower feed roll. The gear 8 is also in mesh with the gear 9 on the driven shaft 7 disposed above the shaft 6 and a shaft 7 carries a second or upper feed roll. This arrangement of gearing provides for rotating the shafts 6 and 7 and their feed rolls in relatively opposite directions to cooperate in feeding the work engaged between the rolls. The shafts 6 and 7 at their outer ends are provided with collars 10—10 for securing the shafts within their bearings against longitudinal displacement.

The uprights are shown as of sectional form and for the upright 2, comprising a pair of spaced vertical posts 11—11 between which the bearings 12 are secured, the bearings being secured in place by means of screws 13 engaged through and into the vertical posts 11—11 and the posts are secured together by means of the bolts 14. Regarding the upright 2^a its structure is similar to that of the upright 2 excepting that the lower bearing block 15 journaling the shaft 6 is rigidly secured by a screw 19 and the upper bearing 16 is vertically slidably mounted between the posts 17.

The forward ends of the shafts 6 and 7 extend beyond the outer side of the upright 2^a to which, respectively, the feed rollers 20 and 21 are fixed. The bearing 16 is vertically movable for separating or spacing the feed rolls to accommodate for various thicknesses of material and for yieldingly urging the upper roll 21 toward the lower roll 20 under the tension of a coil spring 22 seated within a socket formed in the bearing 16. One end of the coil spring 22 is engaged about the free end of a rod 23 and against a nut 25 screw-threaded upon the rod 23. The nut 25 is held against rotation by contact with the spring thereby providing means for adjusting the tension of the spring. The adjusting rod 23 is engaged through a cross piece 26 which connects the upper ends of the posts 17 of the upright 2^a and is provided with a handle 27 with which the rod can be rotated relative to

the nut for adjusting the tension of the spring. A collar 28 is pinned to the rod, this collar engaging the underside of the cross piece 26 for maintaining the rod against displacement relative to the cross piece.

To permit elevating the upper feed roll 21, the bearing block 12 in the upright 2 is hinged-ly mounted by means of the screw 13 and the bearing block 16 is slidably mounted within its upright 2^a. A lever 30 pivoted to the inner side of the upright 2^a has its forward end engaging the under side of the shaft 7 and its opposite end connects with an actuating rod which may be treadle operated or otherwise actuated for swinging the shaft and its parts. The bearing block 16 is limited in its downward movement by engagement against an adjustable abutment serving to limit the depth cut of the knife sustained upon the bearing block. The abutment comprises a screw 32 threaded into the fixed bearing block 15 with the head of the screw bearing against a cutter holder clamp 39 mounted upon the lower side of the bearing block 16. For inserting the work between the feed rolls the lever 30 is actuated to elevate the feed roll 21 whereupon after the work has been inserted, the lever is released bringing the upper roll 21 upon the material under spring tension, so that when the rolls are rotated the work or material will be appropriately fed due to its frictional engagement with the rolls. The slide block 16 is held laterally against displacement by a cross bar 35 which connects the posts of the upright.

A cutter holder 36 is secured within the clamp 39 on the under side of the bearing block 16 with its forward end arranged and extended to provide a guide for the material between the rolls and a base for suitably supporting a stationary cutter or blade 37 having its cutting edge extending over the lower feed roll and adjacent the inner edge of the upper feed roll. The holder is provided with a shank 38 engaged within the clamp block 39 fixed to the under side of the bearing block 16, the clamp block 39 being of any sectional form and adapted to frictionally clamp the shank of the holder which is preferably of square form of cross section, the sections of the clamp being held together by means of a vertical screw 41 and a horizontal screw 42, the screw 41 securing the clamp block to the bearing block.

The body portion of the cutter holder 36 has its upper face recessed to receive the cutter blade 37 which is secured to the holder by means of a screw passed through the axis of the blade, the blade body being of semi-circular form to give it a wide bearing surface within the holder and also enable the same to be adjusted about the axis of the screw for adjusting the cutting angle of the blade relative to the work. The cutting edge of the blade extends radially with respect to the

axis of the cutter and is inclined upwardly for obtaining an appropriate bevel trim to the material passed across the cutter. The cutting edge also is slightly skewed to advance the point end of the blade and presenting its cutting edge to the work to obtain a shear or draw action as the work is fed against the cutter.

The forward edge of the holder is preferably curved and serves as a guide for the edge of the work this edge being indicated at 48. The holder of the cutter is also provided with a guide lip 49 engaging over the upper marginal edge of the work to guide the same downwardly or hold the same against any upward drawing tendency under the action of the knife as the work is fed. This guide or pressure lip 49 is adjustably mounted upon the holder having a dove-tailed connection with the cutter holder for adjusting the same vertically and frictionally held in its adjusted position by means of a screw 50 engaged through and into split portions of the holder. The cutter being fixed to the bearing block 16 unitarily combines with the roll and therefore bears a definite relation thereto, so that no relative adjustment need be made for any change in thickness in sole material to be trimmed unless it is desired to change the degree of chamfering or angle of the cut. As the gauge thickness for soles varies considerably no setting need be made for each thickness of material, the primary feature being to trim the margin preferably from the flesh side to produce a uniform depth of cut. The edge thickness of one sole to another varies according to the gauge thickness of the different stock used, which generally is immaterial, the edge marginal trimming being preferably for the purpose of giving finish to the flesh side and provide a margin over which the shoe upper can be appropriately applied, for such types of shoe in which the sole does not extend materially beyond the upper and for other types to provide a face surface which will not require trimming after the upper is applied.

Another form of lower feeding member is shown in Figure 7. When it is desired to make a greater degree of chamfering cut, the rotary member 51 is substituted for the member 20. A portion 52 of the member 51 at the inner side thereof is of increased diameter. The member 51 is mounted in the same relation to the upper rotary members as member 20, but due to the increased diameter portion 52, the edge of the sole is turned upwardly slightly and more into the blade resulting in a greater degree of chamfering. This type of feeding member is used when an extremely sharp chamfer is desired, otherwise blades having cutting edges of varying degrees of inclination are used as in the previously described form.

The rolls 20 and 21 provided with differential face widths are arranged for extending the face of the lower roll beyond that of the upper to have the cutter over-lie the margin of the work bearing upon the extended portion of the lower roll, so that the cutter as well as the roll compressively engages the work upon the lower roll. This provides a support for the work for the full degree of the cut. The cutter being movably mounted with the upper roller cannot be depressed beyond a depth allowed by the upper roll through its contact upon the work and this insures trimming the work to a uniform edge thickness governed by the thickness of the work. For the margin or edge trimming of the sole, it is only required that the margin surface of the flesh side be uniformly trimmed. The thickness of the sole edge does not necessarily have to correspond in measurement to that of the second sole, so that no knife setting need be made for the varying thicknesses of material for a given range. The trimming is primarily to give finish and appearance to the edge of the sole rather than utility, and the finish is materially marred if the varying trimming presents an undulating or wavy-like appearance. With the marginal edge of the work substantially supported it can be drawn across the cutter for skiving off a uniform amount irrespective of the thickness of the stock.

Having described my invention, I claim:

1. In a device of the class described, a frame, a pair of rotary feeding elements having opposing peripheral surfaces, one of the feeding elements being of less width than the other and adjustable in relation thereto, a cutter holder adjustable with and having a blade disposed at the side of the narrow faced feeding element and above the peripheral surface of the broad faced rotary element, the wide faced rotary feeding element having an increased diameter portion beneath the blade for directing the material edge inserted between the rotary elements upward into the blade for removal of a greater quantity of material from the margin.

2. In a device of the class described, a pair of driven rolls, said rolls peripherally opposed, one thereof journalled for movement relative to the second roll, means for urging said first roll toward the second roll, a cutter holder mounted in fixed relation to the first roll and movable therewith, and a cutter mounted on said holder and having its edge disposed over the surface of the second roll, said holder embodying an abutment edge beneath the cutter for definitely controlling the insertion of the work between the roll and against the cutting edge.

3. In a device of the class described, a pair of driven rolls, said rolls peripherally opposed, one thereof journalled for movement relative to the second roll, means for urging

said first roll toward the second roll, a cutter holder mounted in fixed relation to the first roll and movable therewith, a cutter mounted on said holder and having its edge disposed over the surface of the second roll,
5 and a guiding element engaging the work in advance of the cutter for holding the work firmly against the lower roll.

In witness whereof, I hereunto subscribe
10 my name.

PEARL JOSEPH WENTWORTH.
